Primary Examiner — Tracey J Bell(74) *Attorney, Agent, or Firm* — Ostrager Chong Flaherty & Broitman P.C.(57) **CLAIM**

We claim the ornamental design for a round stone, as shown and described.

DESCRIPTION

FIG. 1 is a top and side perspective view of a round stone; FIG. 2 is a bottom and side perspective view thereof; FIG. 3 is a top view thereof; FIG. 4 is a bottom view thereof; and, FIG. 5 is a side view thereof, all sides having the same side view.

The broken lines in FIGS. 1, 2, 4, and 5 depict portions of the round stone that form no part of the claimed design.
